ATTORNEY

UNITED STATES PATENT OFFICE.

AUGUSTUS J. KEIL, OF NEWARK, NEW JERSEY, ASSIGNOR TO THE
WHITEHEAD & HOAG COMPANY, OF NEW JERSEY.

DESIGN FOR A HEAD-PIECE FOR BADGES.

SPECIFICATION forming part of Design No. 29,610, dated November 8, 1898.

Application filed October 18, 1898. Serial No. 693,927. Term of patent 14 years.

To all whom it may concern:

Be it known that I, AUGUSTUS J. KEIL, a citizen of the United States, and a resident of Newark, in the county of Essex and State 5 of New Jersey, have invented a certain new and useful Design for a Head-Piece for Badges, of which the following is a specification.

My invention is a new and useful design 6 for a head piece or bar, such as is ordinarily employed in connection with a ribbon-badge; and the leading features of the design consist in the general surface ornamentation of the bar, as well as in the marginal configuration of the same, as shown in the accompanying drawings, in which—

Figure 1 is a face or obverse view. Fig. 2 is a back or reverse view; and Fig. 3 is a horizontal section, taken on line x in Fig. 2, of a head-piece for a badge embodying my new design.

In said drawings, a represents the flat surface of the main body of the head-piece, which is rectangular in its general appearance and 15 is surrounded by the upwardly and outwardly inclining sides a' .

At each end bounding the marginal edges formed by said ends of the body a and the contiguous sides a' of said body are angularly-shaped openings a^3 , and said edges terminate in slightly-curved lips a^2 , which project at an angle from the back surface of the body a , substantially as illustrated.

The upper surfaces of each side a' are suitably curved, as shown in the sectional view 35 in Fig. 3, and are, furthermore, ornamented by a marginal configuration and surface ornamentation, (illustrated more particularly in Fig. 1 of the drawings,) the whole forming a 40 highly-ornamented framework surrounding the main body a and extending slightly above the upper flat surface of said body. Thus each longitudinal side of said frame is formed with a pair of hemispheres b and b' , the latter forming an outwardly-curved part of the

marginal configuration, as at c , and from each end of said curved portion extend outwardly in a direction toward the ends of the frame the curved or arched members c' . The upper surfaces of the frame directly back of the members c' are ornamented with inwardly-curving raised portions b^2 and a straight edge b^4 . The ends of said curved members c' , near the hemispheres b and b' , terminate in the spherical or ball-shaped ends b^5 . The longitudinal marginal side edges of said frame portion are completed by the alternating outwardly and inwardly curved parts c^2 and c^3 , respectively, and the upper surface is ornamented with spherical parts b^6 and b^7 and depressions b^8 .

The marginal edges at the ends of the frame portion surrounding the main body a are formed by a pair of oppositely-extending ogee curves d and d' , which terminate at their ends 65 in balls or spherical portions d^3 , and at the center, between said curves d and d' , is a ball or spherical portion d^4 . The surface d^4 of said end portions of the frame is further ornamented by raised and curved ornaments 70 d^5 , as clearly illustrated in Fig. 1. The reverse of said frame portion, as represented in Fig. 2, is provided with a correspondingly-formed ornamentation, which is similar in all respects to that illustrated in Figs. 1 and 3 of 75 the drawings, except that in the reverse the ornamentation is formed by depressions in place of the raised parts found in the obverse.

Having thus described my novel design for 80 a head-piece for a badge, what I claim is—

The design for a head-piece for a badge, substantially as herein shown and described.

In testimony that I claim the invention set forth above I have hereunto set my hand this 85 14th day of October, 1898.

AUGUSTUS J. KEIL.
